UNITED STATES PATENT OFFICE.

JAMES W. BRAINARD, OF PITTSBURG, PENNSYLVANIA.

METALLIC HOOP.

No. 889,100.

Specification of Letters Patent. Patented May 26, 1908.

Application filed March 9, 1906. Serial No. 305,126.

To all whom it may concern:

Be it known that I, JAMES W. BRAINARD, of Pittsburg, Allegheny county, Pennsylvania, have invented a new and useful Improvement in Metallic Hoops, of which the following is a full, clear, and exact description.

My invention relates to metallic hoops for barrels, kegs and similar articles and 10 more particularly to the chime or end hoops of the barrels.

In barrels having wire hoops or hoops of circular cross section difficulty has been experienced in preventing shifting of the hoops 15 on the barrel staves especially of the chime or end hoops, during the frequent handling received by such barrels.

The object of my invention is to provide a metal hoop of suitable shape by which the 20 staves are held together around the heads of the barrel and to provide means by which a wire hoop, having a circular cross section, is securely held in place and its movement on the barrel is prevented.

25 In the drawings, Figure 1 is a sectional view showing my invention as it is applied to hold a wire hoop in place on a wooden barrel. Fig. 2 is a vertical section of the hoop; Fig. 3 is a vertical section on a larger 30 scale showing the hoop as used with a wire hoop of circular cross section and Fig. 4 is a similar detail view without the wire hoop.

The invention consists in a metallic hoop 2 constructed of a thin metal strip having a 35 substantially circular bead 3 formed on the one edge and a semicircular projection or bead 4 on the opposite edge, the beads preferably extending the whole length of the hoop and entirely around the barrels.

40 I have found that by using the usual wire hoop 5 and by employing the auxiliary metallic hoop 2 having beaded edges as shown in the drawings, the wire hoop is securely held in place and will not shift its position 45 on the barrel during handling of the barrel.

The hoop having the beaded edges may be employed without wire hoops; the ends of the hoop may be joined by rivets or may be

welded or otherwise united and other changes may be made without departing 50 from my invention.

I claim:

1. A fastening for barrels comprising a flat, thin metallic hoop having a substantially circular bead on one of its edges and a 55 substantially semi-circular bead or projection on its opposite edge, and a second hoop having a substantially circular cross section, the semi-circular bead on the edge of the flat, thin hoop being arranged to contact with and hold the hoop having a circular cross section in place on the barrel; substantially as described.

2. A fastening for barrels comprising a metallic hoop of substantially circular cross 60 section and a supplemental metal hoop of flat, thin cross section having beaded edges, the semi-circular bead on one edge of the flat, thin hoop being arranged to engage with and retain the hoop of circular cross 65 section in position on the barrel; substantially as described.

3. A fastening for barrels comprising a metallic hoop of substantially circular cross 70 section and a supplemental metal hoop of flat, thin cross section having a circular 75 bead upon one edge and a semi-circular bead on its opposite edge, the semi-circular bead on the supplemental hoop being arranged to engage with and retain the first 80 hoop in position on the barrel; substantially as described.

4. In a fastening for barrels, the combination with a metallic hoop of circular cross section, of a second hoop of flat thin cross 85 section having a semi-circular bead on one edge, said second hoop being arranged to engage with and secure the hoop of circular cross section in position on the barrel; substantially as described.

In testimony whereof, I have hereunto set my hand.

JAMES W. BRAINARD.
